UNITED STATES PATENT OFFICE.

BENJAMIN FRANKLIN, OF CHICAGO, ILLINOIS, ASSIGNOR OF ONE-HALF TO
FRANCIS E. MORSE, OF SAME PLACE.

CALENDAR-CLOCK.

SPECIFICATION forming part of Letters Patent No. 279,143, dated June 12, 1883.

Application filed October 12, 1882. (Model.)

To all whom it may concern:

Be it known that I, BENJAMIN FRANKLIN, of the city of Chicago, county of Cook, and State of Illinois, have invented a new and useful Improvement in Calendar-Clocks, of which the following is a description, reference being had to the accompanying drawings, in which—

Figure 1 shows a front view of the clock-dial, with the hour, minute, and day hands indicated thereon. Fig. 2 is a back view of a part of the dial, showing the calendar mechanism attached thereto. Fig. 3 is a view of the front plate of the frame-work of the clock, showing the connection of the "day-wheel" therewith. Fig. 4 is a face view of the wheel or disk which serves to propel the day-hand on the dial, the reverse side or back of said wheel being shown in Fig. 2. Fig. 5 is a perspective detail view of the detent for controlling the movement of the disk or month-wheel, the secondary stop for assisting therein, and the connection of the same with the dial, which is broken away. Fig. 6 is a transverse sectional view of the calendar mechanism cut through the line 6 6, as shown in Fig. 4. Fig. 7 is a back view of the ratchet-wheel, shown upon the disk in Fig. 4, with its accompanying cam-wheel for indicating the short months. Fig. 8 is a detail view of a movable tooth attached to the month-wheel, and shown in Fig. 2. Fig. 9 is a back view of the "counting" or four-year wheel, showing its eccentric, a front view of said wheel being shown in Fig. 2.

Like letters of reference indicate like parts in the different figures.

In the construction of calendar-clocks little, if any, advancement has been made upon the imperfect and now almost obsolete mechanism requiring special adjustment for all of the shorter months, as well as leap-year. All attempts toward such advancement have embodied such complicated mechanism, or have required such delicacy of adjustment, that they have been largely impracticable, even in the more expensive clocks, while in none, owing particularly to the extreme nicety of adjustment necessary therein, has certainty of action been insured.

My purpose, and the object of my invention, is to provide a calendar-clock mechanism that may be readily applied to the works of an or-

dinary clock without an extra dial or an enlargement of space, and which shall be perpetual in its movement, or, rather, so constructed that it shall automatically indicate all the changes in the various months, including leap-year, which mechanism shall be cheap, simple, and compact in its construction, as well as certain and positive in its action. I accomplish this object by the use of a wheel or disk having thirty-one teeth upon its periphery, and being concentric with the clock-dial. Upon the hub of this wheel, which I shall call the "month-wheel," and concentric therewith, is a star-wheel of seven points connected with the month-wheel by a frictional spring pressing with sufficient force against the month-wheel to revolve the same, except when the latter is purposely stopped. This star-wheel is actuated by a pin in the periphery of the day-wheel—such as is well known to the art—which engages with the cannon-pinion, and revolves once each day, causing one-seventh of a revolution of the star-wheel. This in turn produces a movement of the month-wheel equal to four and three-sevenths notches or teeth on its periphery, each of which represents a day, as shown by the day-hand on the dial. It is apparent that this extended movement of the month-wheel is only necessary once in each year—viz., in February of all years, except leap-year. To prevent it at other times, therefore, I interpose a stop or detent, which is raised by the pin in the day-wheel and allowed to drop into the succeeding notch, when the revolution of the month-wheel is arrested and the star-wheel completes its movement. I also provide means for preventing the fall of the detent until after the pin in the day-wheel has begun to act on the star-wheel. To prevent the detent from dropping into all the notches I provide a dog, which is in the same plane with the month-wheel, and pivoted thereto, and which, when raised to the outer circumference of the month-wheel, prevents the stop from acting thereon, and forms a slide, upon which the latter is carried over one or three teeth, as may be required, to indicate a thirty or twenty-eight day month. The dog is actuated by a cam having a separate projection for each of the short months, which engages with a tooth upon

the dog. This mechanism is sufficient to indicate all the changes except that of leap-year, at which time it is apparent that the dog would be raised, as in other years, and would cause the detent to pass over three teeth. To prevent this I provide a movable tooth or dog, which is actuated by an eccentric making one complete revolution every four years, said dog being placed at the side of the twenty-ninth tooth of the month-wheel, and forming by its movement an elongation thereof every fourth year. This elongated tooth is thereby brought in contact with the detent, thus indicating the twenty-ninth day of February in leap-year. I also provide modifications of the mechanism last described for indicating the short months and the extra day in leap-year, which, together with the devices above mentioned, will be hereinafter more fully set forth and definitely pointed out in the claims.

In the drawings, A represents the month-wheel, having thirty-one teeth upon its periphery, a back view of which wheel is shown in Fig. 2. Said wheel has a cylindrical hub, 25 *a*. (Better shown in Fig. 6.) Loosely attached to said hub *a*, and concentric therewith, is a seven-pointed star-wheel, B, which is retained in position by a bifurcated friction plate or spring, *b*, which partially encompasses said hub, and is pressed into a groove, *b'*, encircling said hub near its end. A depression in the star-wheel and a corresponding projection on the spring-plate *b* at *b''* serves to retain said plate in position and to enable it to be readily removed when desired by springing the same out of the depression, when it can be slid out of the groove. The pressure of the spring-plate *b* against the flange in the hub, formed by the groove *b'*, presses the star-wheel B, with 30 which it revolves, against a shoulder, *b'''*, Fig. 6, producing a sufficient amount of friction to propel the month-wheel A when the star-wheel B is actuated.

Rigidly secured to the back of the dial C (more clearly shown in Fig. 5) is a metal plate, D, upon which is a cylindrical projection or boss, *c*, at the center of the dial, through which the arbor of the hour and minute hands project, and into which the front end of the hub 45 *a* of the month-wheel is inserted, thus forming a pivotal bearing for the latter, on the outer end of which is fixed, against the shoulder *d'*, Figs. 4, 6, and 10, the day-hand *d*, Fig. 1.

Upon the plate D is fixed a post, *e*, Figs. 2 and 5, to which is secured one end of a spring, *e'*, the other end of which is bent in a V shape, and the whole so adjusted that the bent portion may press between the teeth of the day-wheel and form a stop to keep the same in position, when it is not otherwise secured, in the manner common for such purposes.

Upon the upper portion of the plate D is a pin, *f*, Figs. 2 and 5, upon which is pivoted a detent or stop, E, clearly shown in the drawings, having a projecting arm, *g'*, extending laterally outward and downward therefrom, at

such an angle as will enable the pin in the day-wheel to engage therewith, so as to lift said arm. The forward end of the detent E drops down into the notches of the month-wheel A. To secure certainty of action in this respect the detent is made to project back of the pivot *f*, and to engage with a spring, *f'*, which presses upward, thus forcing the opposite end of the detent down. A different spring 70 might be used in a different position with the same result.

Upon the end of the detent E, which is intended to drop into the notches of the month-wheel, is an upward projection, to which is riveted or otherwise secured a spring, *g*, the purpose of which is to hold up the detent when raised by the day-wheel in the manner and for the purpose hereinafter more fully described. This spring should be so adjusted that when not under tension the distance between its lower end and that of the detent should be less than the length of the notches in the month-wheel, as well as less than the width of the teeth, to prevent straddling them. 85

F, Fig. 3, shows the front plate, forming a part of the frame for supporting the train of an ordinary clock. *h* is the cannon-pinion or hour-wheel, the arbor *h'* of which extends through the hub *a* of the month-wheel. Secured to the plate F by a post in the usual manner, and engaging with the hour-wheel *h*, is the day-wheel *i*, the pin *i'* of which engages with the arm *g'* and the star-wheel B, and may also engage with a disk in the usual manner, and reveal in succession the name of each day of the week through a suitable slot in the dial, as shown in Fig. 1.

On the front face of the month-wheel A, and next to the dial, is placed a twelve-toothed ratchet-wheel, G, Figs. 4 and 7, provided with stop *j*, constructed in the usual mode, secured to said month-wheel, and which engages with the teeth of said ratchet as the same revolves.

Between the ratchet-wheel G and the month-wheel, and secured rigidly, so as to move with said ratchet, is a cam-wheel, H. (Shown in Fig. 7, and indicated in dotted lines in Fig. 4.) The cam-wheel H has five projections, *k*, the fifth of which is longer than the others. On the side of the month-wheel A, and pivoted at *l*, near its outer circumference, I place a movable dog, I, so adjusted as to drop readily between the ratchet-wheel G and the month-wheel A, and having a projection or tooth, *m*,

which is hidden by the ratchet G in Fig. 4, but shown in Fig. 10, to fall into the spaces between the projections or teeth *k* of the cam-wheel H. Such tooth should be so adjusted that when resting on any one of the four shorter projections, *k*, a portion, *n*, of the dog I may be pushed out so as to be even with or extend beyond the outer end of the thirty-first tooth of the month-wheel and cover the notch between that and the thirtieth tooth to prevent an engagement 120 of the detent E with the former. When the tooth *m* of the dog I rests upon the longest pro-

jection *k* of the cam-wheel *H* the dog *I* should be so shaped as to cover three teeth of the month-wheel—viz., the twenty-ninth, thirtieth, and thirty-first. A staple or keeper, *o*, Fig. 4, is secured to the month-wheel, beneath which the loose end of the dog *I* moves, and which serves to limit the outward movement of said dog and to hold the same laterally in position. A pin, *p*, secured rigidly to the wheels *G* and *H*, and forming their axis, passes through them and through the month-wheel *A* into a third wheel, *J*, Figs. 2 and 6, to which it is detachably secured, preferably by a pin, as shown in Fig. 2, in such manner as that the wheels *G*, *H*, and *J* may revolve in unison.

Engaging with the wheel *J*, Fig. 2, is a “counting-wheel,” *K*, Figs. 2 and 9, which likewise revolves upon a post secured to the month-wheel. On the inner side of the counting-wheel *K* is an eccentric, *q*, Fig. 9, which serves by its revolution to elongate a supplementary tooth, *L*, Figs. 2 and 8, the hole *q'* therein being made to fit the eccentric *q*, and the end of said tooth being held in position alongside of the twenty-ninth tooth of the month-wheel by the staple or keeper *r*, which serves as a guide for the tooth in its reciprocating movement.

Upon the plate *D*, sufficiently near to the boss *c* to engage the ratchet-wheel *G* with each revolution of the month-wheel, I place a post or pin, *s*, which is rigidly secured to the plate *D*.

In place of the mechanism described for registering the short months, a single wheel adjusted upon the face of the month-wheel so as to revolve once in four years may be used, said wheel having upon its periphery twenty teeth, sixteen of which may be of equal length, arranged in sets of four, between which are four longer teeth, three being of equal length and one of intermediate length between them and the short teeth, said teeth engaging with the tooth of the dog *I*, in like manner as those of the wheel *H* engage therewith, the sixteen shorter teeth throwing said dog out to provide for the thirty-day months, the three longest teeth for February when the same has twenty-eight days, and the intermediate tooth for February of leap-year. By means of this mechanism the tooth *L* may be dispensed with; but owing to the finer adjustments necessary in its adaptation I regard the same as an inferior equivalent of the mechanism above described.

Secured to the back of the dial by a post in the usual manner I place a twelve-pointed disk, *O*, Fig. 2, in such proximity to the month-wheel as that its points or teeth may be engaged by a pin preferably projecting from the front of said month-wheel. Upon the front of said disk *O* may be shown the names of the months, which may be revealed through a slot in the dial, as indicated in Fig. 1, in the manner frequently adopted.

Having thus described the various parts em-

bodying my invention, I will proceed to describe their operation.

Assuming the various parts of said mechanism to be adjusted with reference to each other in the manner above described, the action of said parts upon each other is as follows: As the wheel *i* revolves the pin *i'* engages with the arm *g'* of the detent *E*, and raises said detent out of the notch in which the same has fallen in the periphery of the month-wheel *A*, the auxiliary stop *e* in the meantime resting between the teeth of said month-wheel and preventing any possible movement of the same. Thereupon the spring *g*, which should be very weak, assuming its normal position, as shown in Fig. 5, comes in contact with the top of the succeeding tooth of the month-wheel and rests thereon, thereby preventing the detent from falling back into the notch from which it has just been raised. Leaving the detent *E* thus resting upon the top of said tooth, the pin *i'* passes on and engages with the star-wheel *B*, which, being held by the friction-plate *b* against the shoulder of the month-wheel, causes the latter to revolve until the detent *E* drops into the succeeding notch, which, being wider than the width of the detent and the space occupied by the bent spring *g*, allows said detent and spring to drop therein, when, the friction of the star-wheel on the month-wheel being greater than the resistance of the spring *g*, which I prefer to make very light, said spring is pressed against the detent and prevented by the action of the auxiliary stop *e* from producing a backward movement of the month-wheel *A*, but is ready to again spring outward as soon as the detent is raised and support the same upon the end of the succeeding tooth until the month-wheel is turned. As the movement of the month-wheel is controlled by the day-wheel, it is apparent that its action is very slow, requiring several minutes to move from one notch to another. This insures certainty of action on the part of the detent, in which respect it differs from the calendar-clocks heretofore in use, the corresponding changes in which are sudden, and therefore often uncertain. The pressure of the spring in the rear of the detent serves further to insure its positive action.

As the clock may be adjusted to produce the movement of the day-wheel during the night, the few minutes required for that are therefore unobjectionable. As previously stated, the friction-wheel *B* makes one-seventh of a revolution for each revolution of the day-wheel, which is equivalent to four and three-sevenths teeth of the month-wheel; but as this extreme movement is required but once in each year the stop *E* and other mechanism is interposed to meet the required modifications. It is apparent that the wheel *B* might move continuously, and by the interposition of the detent and other mechanism in the manner described would accomplish the same result in substantially the same way, which I should regard as but an inferior equivalent for my invention.

tion. As the month-wheel revolves the teeth of the twelve-pointed ratchet-wheel G engage with the stationary pins s, thereby moving said wheel one-twelfth of a revolution; and hence it follows that the cam-wheel H, being rigid with the wheel G, revolves but once per year, and, the five projections thereon being adjusted with reference to the five short months, serve to throw the dog I out during said months, and, the detent E being thereby prevented from dropping into the notches of the month-wheel, rides over the same and the teeth until the projection on said dog, which is at the side of the thirty-first tooth, is passed, when it again drops successively into the notches; and, as in the next month the tooth m of the dog I has dropped into a depression in the cam-wheel H, the detent is permitted to engage all the teeth of the month-wheel, and thus indicate thirty-one days on the dial. The four projections on the cam-wheel H being of an equal length, the dog I is thrown out sufficiently to cause the detent E to ride over one notch, thus indicating thirty days for each of those months. The fifth projection of the cam-wheel H being longer, throws the dog out sufficiently to cover three notches or teeth, thus indicating twenty-eight days on the dial; but it is obvious that this movement is constant, thus making no provision for leap-year; hence I am compelled to adopt means to modify it at that time. Connecting the wheel J to the axis of the wheel G a yearly movement is produced in the former, which, engaging with the counting-wheel K, revolves it once in four years by four successive movements, and as the tooth L is adjusted upon the eccentric q it is apparent that every fourth year it will project outward from the twenty-ninth tooth, remaining in that position for twelve months. The detent E is thus caught upon the tooth L, and, arresting the movement of the month-wheel, causes the twenty-ninth day of February in each leap-year to be indicated upon the dial.

In order to set the calendar it is but necessary to press the month-hand gently to the right, in which case, if the detent E is raised, as described, the hand may be readily moved, otherwise it is advisable to wait until this action takes place, which usually occurs about five o'clock in the afternoon.

It is obvious that the friction-wheel B may be replaced by a pinion engaging directly with the day-wheel, and propelling the month-wheel by frictional contact may move constantly; but this I should regard only as an inferior equivalent of the star-wheel B, and a less preferable mode of applying my invention.

In lieu of the mechanism hereinbefore described, the last three teeth on the month-wheel may be cut away and movable teeth capable of elongation, as required to indicate the varying number of days in each month, (the same being operated by cams or eccentricities properly adjusted for that purpose,) may be inserted, in which case the dog I may be

dispensed with, as there would then be nothing to engage the detent between the twenty-eighth and first tooth of the month-wheel when said movable teeth were not thrown out. One or three movable teeth on one side of the month-wheel may be thrown out or withdrawn, so as to indicate the short months in all years except leap-year, at which time a fourth tooth may be thrown out on the opposite side of the month-wheel to engage the detent for the twenty-ninth day of February, at which time it is obvious that all the others would be withdrawn.

A further modification, and a somewhat simpler one in its construction, would be, after cutting away said last three teeth, to provide teeth upon the dog I, in which case said dog may be made to engage directly with the ratchet-wheel G, instead of the cam-wheel H, said ratchet-wheel G being provided with notches or depressions of varying depths, into which the tooth of said dog may drop, thus withdrawing one or more of the teeth of said dog I from contact with the detent E, as may be required to indicate the short months, which, it will be observed, is the reverse of the operation above described, the dog I being withdrawn, instead of thrown out, to indicate the short months. In the event of using this last-described mechanism a spring should be attached to the free end of the dog I for the purpose of holding the same in the depressions of the ratchet when not required to be raised.

Having thus described my invention, what I claim, and desire to secure by Letters Patent, is—

1. A calendar-clock provided with a month-wheel having thirty-one teeth, and actuated by a wheel having frictional contact therewith, and adapted to move said month-wheel each day a distance equal to four teeth upon its periphery, substantially in the manner and for the uses and purposes described.

2. A calendar-clock provided with a month-wheel having thirty-one teeth, and frictional mechanism for moving the same each day a distance sufficient to move the hand on the dial from the twenty-eighth day of February to the first day of the succeeding month, combined with a detent adapted to engage successively with all of the teeth of the month-wheel to modify said extended movement, and a dog operated by a wheel having suitable projections of varying length, so adjusted as to raise said dog to cover one or three teeth of the month-wheel for the various short months, said dog forming, when raised, a slide upon which said detent may ride over the adjacent teeth, in the manner and for the uses and purposes substantially as described.

3. A calendar-clock provided with a month-wheel, and frictional mechanism for moving the same each day a distance of not less than four teeth on said wheel, a detent capable of engaging successively with all the teeth of the month-wheel to modify said four-day move-

- ment, a dog, with means for raising the same to form a slide for said detent over one or three of said notches, and a movable tooth placed at the side of the twenty-ninth tooth of said month-wheel, and means for elongating said tooth every fourth year, in the manner and for the uses and purposes substantially as described.
4. In a calendar-clock, a detent for regulating the daily movement of the month-wheel, said detent being provided with a spring on the side of the tooth of said detent, and capable of resting its lower end upon the outer end or extremity of the next succeeding tooth of said month-wheel, and thereby temporarily sustaining said detent in a raised position until said succeeding tooth has passed beneath the tooth of said detent, substantially as described.
5. In a calendar-clock, the combination of a month-wheel having thirty-one teeth in its periphery, a detent capable of engaging the same, a movable dog capable of covering three of said teeth, and a wheel with projections of varying length on its periphery engaging with said dog, 25 all constructed and adjusted substantially in the manner and for the purposes described.
6. In a calendar-clock, the combination of a month-wheel, a twelve-toothed ratchet-wheel, a stationary pin to engage the same with each 30 revolution of the month-wheel, a five-pointed cam-wheel having one of its projections longer than the others, said ratchet and cam wheels moving in unison with a wheel on the opposite side of the month-wheel, which engages a 35 counter-wheel adjusted to revolve once for every four revolutions of said three last-named wheels, an eccentric upon the axis of said counter-wheel, and a movable tooth adjusted thereon, substantially for the uses and purposes described.

BENJAMIN FRANKLIN.
